CLAIM

The ornamental design for a solar module, as shown and described.

DESCRIPTION

The patent or application file contains at least one drawing executed in color. Copies of this patent or patent application publication with color drawing(s) will be provided by the Office upon request and payment of the necessary fee.

FIG. 1 is a color perspective view of a solar module showing our new design;

FIG. 2 is a front color view thereof;

FIG. 3 is a back color view thereof;

FIG. 4 is a top color view thereof, with a partially enlarged area shown for ease of illustration;

FIG. 5 is a bottom color view thereof, with a partially enlarged area shown for ease of illustration;

FIG. 6 is a first, side color view thereof, with a partially enlarged area shown for ease of illustration; and,

FIG. 7 is a second, side color view thereof, with a partially enlarged area shown for ease of illustration.

1 Claim, 7 Drawing Sheets
